UNITED STATES PATENT OFFICE.

DANIEL E. HENING, OF PHILADELPHIA, PENNSYLVANIA.

DISPLAY AND REGISTER APPLIANCE.

SPECIFICATION forming part of Letters Patent No. 634,619, dated October 10, 1899.

Application filed July 11, 1899. Serial No. 723,464. (No model.)

To all whom it may concern:

Be it known that I, DANIEL E. HENING, a citizen of the United States, residing at the city of Philadelphia, in the county of Philadelphia and State of Pennsylvania, have invented certain new and useful Improvements in Display and Register Appliances, of which the following is a specification.

My invention has relation to an appliance having means and mechanism connected therewith for the simultaneous display therein and registration therefrom of maps, charts, engravings, photographs, time-tables, &c., and in such connection it relates particularly to the general construction and arrangement of such a desk or other similar appliance for the said purposes.

The principal objects of my invention are, first, to provide a desk or similar appliance for the display and register of maps, engravings, photographs, plans, time-tables, &c., by the employment of a traveler-apron which is adapted to have printed, stamped, or impressed thereon the matter to be exposed, and which apron by being manipulated actuates simultaneously a registering device to indicate the travel of the apron in respect to exposed portions thereof, and, second, to provide in an appliance of the character described means to maintain the apron not only taut and in any position shifted, but also to insure the actuation of a registering device by said apron working in unison with each other.

My invention, stated in general terms, consists of a display and register appliance when constructed and arranged in substantially the manner hereinafter described and claimed.

The nature and scope of my invention will be more fully understood from the following description, taken in connection with the accompanying drawings, forming part hereof, in which—

Figure 1 is a front elevational view of an appliance embodying the features of my invention. Fig. 2 is a vertical sectional view through the desk of Fig. 1 and also illustrating the internal mechanism in side elevation of my said invention. Fig. 3 is a view in section with the front of the desk removed in

order to expose to view the interior mechanism for operating the apron containing the display of matter from the desk and for controlling the index or finger and register for defining the character of display matter 55 adapted to be exposed from the desk. Fig. 4 is a longitudinal section through the upper portion of the desk with the vertically-inclined face-plate and framework of the desk removed to expose to view the operating 60 mechanism for the apron, and Fig. 5 is an enlarged elevational view in detail of the mechanism for operating the register or index-finger of the desk.

Referring to the drawings, A represents a 65 desk provided with an inclined fixed face having an opening a, within which is secured a pane of glass a'. Above the face or table of the desk A is provided an upright framework a², in which is adapted to be inserted 70 and secured in a space a³ a map, chart, or other matter, and below the space a³ is provided an oblong panel a⁴, adapted to contain an index as to the matter displayed on an apron located within the desk and which will 75 be presently fully explained. Within the desk A is provided a roll or drum B, to which one end of an apron C is secured, the opposite end of said apron being secured to a roll or drum B'. The apron in passing from the 80 roll or drum B is guided over a small roll c. It then passes over a roll c', located in the front end of the desk and in close proximity to the face of the desk on the underside thereof, and then passes backward under a tension-roll c² at the rear of the face of the desk on the underside, whereby the apron is brought close to the glass face of the desk, as will be seen from Fig. 2. The apron then passes over a tension-roll c³ in a vertical direction 85 close to the upright framework of the desk over a roll or drum d, located in that part of the desk, turning the same. The apron then passes over, respectively, the two tension-rolls c⁴ and c⁵ and then in a downward direction and winds onto the drum B', to which it is secured at one end thereof. This apron C is 90 adapted to contain printed, engraved, or other matter to be exposed through the glass face of the desk. At each end of the drum B and 95 100

on the shaft b^6 thereof are arranged reels e , to which one end of a cord or rope f^6 is secured, which passes over a guide-roll f in a vertical direction to and over a roll f' and then passes over a series of rolls f^2 and f^3 , which latter rolls are secured to a counter-weight f^4 , from whence the wire or other type of cord or rope f^6 passes upward and is secured to the interior of the framework of the desk, as illustrated in Fig. 3. The lower roll or drum B' is provided with a similar arrangement of reel, rolls, cord, and counterweights, as hereinbefore fully explained. As illustrated in Fig. 2, the cords or ropes f^6 of the upper drum B are wound around the reel e from the underside, while the cords or ropes f^6 of the lower drum B' are wound onto the reel e' from the upper side thereof. If the upper drum B is turned in the direction of the arrow in Fig. 2, the cords f^6 will be wound onto the reels with their counterweights lifted in such winding, while the cords or ropes f^6 of the lower drum B' will be wound off of the reels and their respective counterweights lowered. The tendency of the upper drum to unwind its cords or ropes through the intervention of its counterweights will be checked by the tendency of the lower drum to wind on its cords or ropes through the action of their counterweights, whereby it will be observed that the apron C will remain in the position shifted and always under such tension as to be maintained taut. At one end of the uppermost guide roll or drum d is secured a pulley g , over which passes a cord or belt g' , which is guided over rolls g^2 and passes to a similar roll g^3 on the opposite side of the upright portion of the desk. This roll g^3 is secured to a spindle or threaded rod g^4 , preferably held in adjustable bearings g^5 and g^6 . On the threaded spindle or rod g^4 is mounted a nut g^7 , with an extension or arm g^8 , which enters an oblong slot g^9 , provided in the upright surface of the desk A , and to the end of which arm g^8 is secured a pointer g^{10} . On each side of said slot in the desk-framework is provided an index or register g^{11} for the printed, engraved, or other type of matter contained upon or impressed into the apron C . By passing the apron C over the uppermost roll or drum d the same will be turned, and this motion will be transmitted by a cord g' to the spindle or rod g^4 , thereby actuating the same and shifting the pointer or finger along the slot of the index or register of the desk either upward or downward, according to the direction of movement of the apron C .

The arrangement and operation of the pointer or finger of the index or register will be regulated by the uppermost guide roll or drum d , which roll is controlled by the movement of the apron. It will be seen, therefore, that the particular or desired matter contained on the traveler-apron C may be indicated by the pointer or finger g^{10} on the register g^{11} . The index on the panel of the desk serves simply

and only to define what particular matter contained on the apron is susceptible of being exposed and at what letter or symbol of the register g^{11} by the shifting of the pointer g^{10} thereof the particular matter in detail of the apron can be exposed through the glass face of the desk A . As illustrated, the upper drum B is driven by a sprocket-chain h , engaging a sprocket-wheel h' , located on the shaft of said drum B , and a sprocket-wheel h^2 on a shaft h^3 , journaled to the lower or horizontal portion of the framework of the desk A and operated by a hand-crank h^4 , whereby through the motion directly imparted to said drum B the apron C is operated in forward and backward directions. The respective counterweights for the drums B and B' are preferably guided between rods i and i' in the interior of the desk A . The horizontal portion below the glass face of the desk may be provided with a drawer a^{10} , as illustrated in Fig. 4; but when that portion of the desk is dispensed with the operating mechanism hereinbefore described for actuating the drum B may be omitted and said drum directly driven by a hand-crank secured to the shaft of said drum.

Having thus described the nature and objects of my invention, what I claim as new, and desire to secure by Letters Patent, is—

1. A display or register appliance, comprising a traveler display-apron, a roll or drum over which said apron passes and actuated by said apron, a threaded spindle or rod carrying a movable pointer, pulleys mounted on said spindle or rod and roll or drum and a cord passing over said pulleys to permit of the actuation of said pointer, simultaneously with the travel of said apron, substantially as and for the purposes described.

2. A display or register appliance, comprising a traveler-apron, a roll or drum over which said apron passes and actuated by said apron, a threaded spindle or rod carrying a movable nut with a square extension located in an oblong slot of the appliance and provided with a pointer, a register located alongside of said slot, pulleys connected with said roll or drum and spindle or rod and a cord passing over said pulleys adapted to transmit the motion of said roll or drum to said pointer to move the same along said register, substantially as and for the purposes described.

3. A display or register appliance, comprising a traveler-apron provided with printed or other matter, the ends of said apron connected with drums, means actuated by said drums tending to turn the same in opposite directions to maintain taut the apron connected with both drums and in any shifted position thereof, a roll or drum over which said apron passes and actuated by said apron and said means producing necessary friction between said apron and roll or drum to insure its positive movement, a threaded spindle or rod carrying a nut with a square extension located

in an oblong slot of the appliance and a pointer, pulleys connected with said roll or drum and spindle or rod and a cord passing over said pulleys and actuating said pointer simultaneously with the travel of said apron, substantially as and for the purposes described.

In testimony whereof I have hereunto set my signature in the presence of two subscribing witnesses.

DANIEL E. HENING.
